HOLDER FOR FOOD PAN FOR PETS

Tony Robert, 5701 Urbana, Houston, Tex.

Filed July 8, 1963, Ser. No. 75,701

Term of patent 14 years

(Cl. D12—2)

Fig. 1

Fig. 2

Fig. 3

The undisclosed side and end of the holder for food pan for pets are the same in appearance as the side and end disclosed.

I claim:
The ornamental design for a holder for food pan for pets, as shown and described.
